Specification of Letters Patent.

Patented Jan. 5, 1915.

Application filed March 28, 1914. Serial No. 827,840.

To all whom it may concern:

Be it known that I, WILLIAM BURLINGHAM, a citizen of the United States, residing at Newport News, county of Warwick, State of Virginia, have invented a new and useful Pneumatic Impact-Tool, of which the following is a specification.

In large industrial plants, such as shipyards, boiler-works, stone dressing plants and the like, where large numbers of pneumatic hammers for riveting, chipping, calking and kindred uses are constantly employed, the problem of economically furnishing, keeping up or increasing the compressed air equipment for the operation of said tools has become an important economical item in shop management, and the primary object, therefore, of my invention is to provide a novel construction of pneumatic hammer, having a novel fluid distribution system therein, whereby the cost of maintenance of the compressed air equipment is greatly reduced, and wherein the greatest possible efficiency can be attained with the greatest economy in the volume of the motive fluid consumed. Formerly, when comparatively few pneumatic implements were used in large plants, as even now in smaller establishments where but a small number of such tools are used, the question of the quantity of the cubic volume of air used was given but little consideration, as an air compressing plant supplying a sufficient amount of air under a given pressure could usually be erected at a reasonable outlay, and without occupying an excessive area. Usually, the quantity of air consumed by the pneumatic hammering tools was more or less ignored, so long as the results in power of the tools is attained. At the present time, however, in large industrial plants, where pneumatic tools and other pneumatic appliances are extensively used, the size and initial expense of the air compressors and the space occupied by them, as well as the power and fuel required for their daily operation, and the incident cost of their installation, operation and maintenance, have assumed proportions of such magnitude as to require careful attention, and have become of sufficient importance to require the careful consideration of remedies to reduce unnecessary expense in this connection, and

it is with the object of obtaining much greater efficiency from a given volume of air at a given pressure in a pneumatic impact tool for riveting, chipping or analogous uses, that my novel tool is designed.

To the above ends, my present invention consists of a novel construction of a fluid distribution system for portable, manually held pneumatic impact or hammering tools, of that class wherein the forward end of the cylinder is open for the insertion of the shank of the working tool, and wherein the reciprocating piston or plunger preferably hammers directly upon said shank, said plunger being actuated by air or other fluid, and said tools being employed particularly in metal work, such as riveting, chipping, calking or hammering, and in all similar operations, wherein the use of a hammer or mallet and chisel have heretofore been employed.

In carrying out the broad principle of my present invention, I apply my novel fluid distribution system to a pneumatic hammer, preferably of such size as to be portable, and manually held in the hand of the user, the forward end of the tool cylinder being preferably adapted to be normally open and to have the shank of the chisel, button set or other working tool inserted therein, while my novel construction of differential reciprocating plunger which I employ, is adapted to hammer directly on said shank.

In carrying out my invention, I employ a novel construction of pneumatic tool cylinder and its adjuncts having a differential bore or piston chamber therein, said piston chamber being adapted for the reception of a novel plunger having differential piston areas, in conjunction with which I employ a novel construction of coacting high pressure inlet controlling valve, and a novel construction of low pressure exhaust controlling valve, all in conjunction with a receiver common to said valve chambers and piston chamber, the foregoing elements being collocated with my novel construction of tool cylinder, which is preferably provided with a grasping handle and throttling valve mechanism of suitable construction at its rear end, the forward end of said tool cylinder being preferably open for the insertion

of the shank of the chisel, button set or other working tool. As a result of this collocation of high pressure inlet controlling and low pressure exhaust controlling valves, in combination with the receiver and my novel construction of differential piston chamber and hammering plunger provided with the differential piston areas, I am enabled to effect a saving of twenty per cent. over the expense of operation of pneumatic tools now in use, and to utilize to a maximum extent the expansive effect of the compressed air or the motive fluid which is initially used at high pressure, and I further simultaneously employ high pressure live air and low pressure air to augment the velocity or momentum of the hammering plunger prior to or during the act of striking its blow directly upon the shank of the working tool.

To the above ends, my invention therefore consists in its broad aspects of a novel fluid distribution system for pneumatic hammers, wherein I utilize to a greater extent than heretofore, the expansive properties of the compressed air employed to effect the reciprocations of the differential plunger.

My invention further consists of a percussion tool, wherein the compressed air is used expansively in a novel manner, so that my novel construction of differential hammering piston is impelled directly upon the shank of the working tool during its striking blow by the high-pressure live-air and by low-pressure air simultaneously applied thereto.

It further consists of a pneumatic hammer having a novel construction of differential hammering piston which is returned from the shank of the working tool by low-pressure air.

It further consists of such a tool in which the valve controlling the piston movement is actuated by the low-pressure air.

It further consists of such a tool in which the high-pressure live-air is substantially only used for initially impelling the differential hammering piston toward the working tool.

It further consists of such a tool in which high-pressure air is solely employed for the hammering blow of the differential piston.

It further consists of an improved arrangement of the operative parts of such an impact tool, whereby the length of the tool is reduced as compared with other tools of similar power.

It further consists of an improved construction of such a tool whereby the weight of the tool proportionate to its power is greatly reduced.

It further consists of other novel features of construction, all as will be herein-after fully set forth.

For the purpose of illustrating my inven-

tion, I have shown in the accompanying drawings, one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a diagrammatic view of the barrel, hammering plunger, valve-chambers, valves and passages of my improved impact tool, illustrating the elements in their respective positions when the plunger is at the beginning of its hammering stroke. Fig. 2 represents a similar view of said elements, illustrating the same in their respective positions when the plunger is at the extreme of its hammering stroke. Fig. 3 represents an axial section of one form of the tool. Fig. 4 represents a transverse section of the hammer, taken on the line $w-w$ in Fig. 3.

Similar numerals of reference indicate corresponding parts in the figures.

Referring to the drawings, the reference numeral 1 indicates the barrel of the tool which has the usual axial bore, 2, which forms the large-diameter working cylinder and which has a tool-socket, 3, at its lower end, or any other means for holding the shank of the working tool, such as a rivet set, chisel, calking-tool or other percussion tool, and which cylinder forms the low-pressure and return cylinder. The upper open end of the barrel has a circumferential flange, 4, engaged by an internally flanged coupling-sleeve, 5, formed with an internal screw-thread engaging the lower externally threaded end of a handle-socket, 6, having a handle, 7, of any suitable or preferred form. The handle is here illustrated as of the so-called closed type, and the coupling may be of any other desired or preferred form commonly employed in pneumatic hammers. The handle has a live-air inlet-nipple, 8, for the attachment of the air-hose, a live-air duct, 9, through it and controlled by a throttle-valve, 10, and a trigger, 11, for operating such valve. All of these parts may be of any preferred construction and design, being elements usually found in tools of this type and forming no part of my present invention.

The lower end of the handle-socket which abuts against the upper end of the barrel, has preferably a reduced portion, 12, which fits into the upper end of the large-diameter cylinder, and said socket has a smaller-diameter bore which forms the high-pressure working-cylinder, 13, in axial alignment with the large-diameter cylinder and closed at its upper end. A plunger is reciprocable

in the two cylinders and has a cylindrical small-diameter piston, 14, having a sliding fit in the small-diameter cylinder, and a large-diameter piston, 15, at its lower end, 5 having a sliding fit in the large-diameter cylinder and forming the low-pressure piston. The small-diameter piston, which is the high-pressure piston, has a circumferential groove, 16, near its upper end, forming an annular distributing port, and a similar circumferential groove, 17, at a distance from its lower end and from the large-diameter piston, forming another annular distributing port. Two enlargements, 18 10 and 19, are formed in the body of the handle-socket and at one side of the same, being parallel to each other and to the cylinder in the socket, and cylindrical valve-blocks, 20 and 21, are secured in said housings and form respectively a high-pressure 20 and a low-pressure valve-chamber, in which, respectively, a high-pressure valve, 22, and a low-pressure valve, 23, are slidable.

A receiver, 24, is provided in the tool and is formed, in the illustrated form of tool, by a number of longitudinal bores, 25, in the walls of the tool-socket and connected at their ends by annular chambers, 26. In the diagrammatic views, Figs. 1 and 2, such 30 receiver is illustrated as a plain cylindrical vessel.

The high-pressure valve-block 20 has a smaller-diameter bore, 27, and a larger-diameter bore, 28, and the upper end of the large-diameter bore has a port, 29, with 35 which a distributing passage, 30, communicates, and the opposite end of said passage communicates through a port, 31, with the high-pressure cylinder at a distance from the upper end of the same. The large-diameter bore has an annular port, 32, which communicates through a distributing passage, 33, with the upper end of the high-pressure cylinder. An annular port, 34, 40 surrounds the large-diameter valve-bore adjacent said latter port and communicates by a passage, 35, with the live-air inlet duct 9. A restricted port, 36, surrounds the lowermost end of the large-diameter bore 45 and is constantly connected to the live-air duct by a passage, 37. An annular port, 38, surrounds the upper end of the small-diameter bore and communicates by a passage, 39, with the upper end of the large-diameter low-pressure cylinder. An annular port, 40, 50 surrounds the small-diameter valve-bore and communicates through a passage, 41, with the receiver, 24. An annular port, 42, surrounds the lower-end of 55 the small-diameter valve-bore and communicates through a passage, 43, with a port, 44, in the high-pressure cylinder at about the middle of the same and is adapted to be uncovered by the small-diameter 60 high-pressure piston of the plunger when

the latter is at the extreme of its down-stroke. The valve 22 which is slidable in the valve-chamber has two pistons, 45 and 46, which fit in the large-diameter valve-bore, and two pistons, 47 and 48, which fit 70 in the small-diameter valve-bore.

The low-pressure valve-block 21 has a large-diameter bore, 49, and a small-diameter bore, 50, and the upper end of such large-diameter bore has a port, 51, communicating through a passage, 52, and a port, 53, with the small-diameter high-pressure cylinder at a point registering with the upper port-groove 16 in the upper end of the small-diameter high-pressure piston 80 of the plunger, when the latter is at the extreme of its down-stroke, and a port, 54, in the high-pressure cylinder registers with said port 53 and with such port-groove, when the plunger is in said position, and 85 communicates with the receiver through a passage, 55. A port, 56, extends from said passage 52 from the upper end of the large-diameter low-pressure valve-bore into the small-diameter high-pressure cylinder and 90 registers with a port, 57, in said cylinder communicating by an exhaust-passage, 58, in the barrel with the atmosphere, and with a port, 59, in the cylinder and communicating by a passage, 60, with the passage 30 95 connected to the upper end of the high-pressure valve-chamber. Said three registering ports are placed in communication by the annular port-groove 17 in the high-pressure piston when the plunger is approaching the extreme of its up-stroke or return-stroke as seen in Fig. 1, so that the upper ends of both valve-chambers can simultaneously exhaust. An annular exhaust-port, 61, surrounds the upper end of 100 the large-diameter bore of the valve-chamber and communicates with the atmosphere, and an annular port, 62, surrounds said bore below the exhaust port and communicates with the lower end of the low-pressure cylinder by a passage, 63. An annular port, 64, 105 surrounds the large-diameter valve-bore below said latter port and communicates with the upper end of the high-pressure cylinder through a passage, 65. A restricted annular port, 66, surrounds the lower end of the large-diameter low-pressure valve-bore and has constant communication with the live-air inlet-duct by a passage, 67. An annular port, 68, 110 surrounds the small-diameter low-pressure valve-bore near its upper end, and communicates with the upper end of the large-diameter low-pressure cylinder by a passage, 69. An annular exhaust port, 70, 115 surrounds the small-diameter low-pressure valve-bore, near the lower end of the same, and communicates with the atmosphere by a passage, 71. The low-pressure valve 23 has two large-diameter pistons, 72 and 73, 120

125 and 130

and two small-diameter pistons, 74 and 75, respectively slideable in the large-diameter and small-diameter valve-bores.

In explaining the operation of the hammer, the several parts may be assumed to be in the positions illustrated in Fig. 1 of the drawings. When the high-pressure or live-air is admitted into the inlet-duct 9, such motive fluid passes between the two large-diameter pistons 45 and 46 of the high-pressure valve which is in its upper position, and into the upper end of the high-pressure cylinder through the passage 33, forcing the plunger downward to deliver its blow upon the working tool. Whatever air is in the lower portion of the low-pressure cylinder is forced out by the low-pressure piston through the passage 63 to the port 62 in the large-diameter bore in the low-pressure valve-chamber, whence it exhausts through the upper exhaust-port 61 therein, the two large-diameter pistons 73 and 72 of the low-pressure valve, which is in its upper position, connecting the port of said passage and the exhaust. When the high-pressure piston in its down-stroke uncovers the port 31 in the high-pressure cylinder, the live-air passes through the passage 30 to above the high-pressure valve, forcing the same downward to the position illustrated in Fig. 2, cutting off the live-air supply above the piston. The high-pressure piston, having gone down to the extreme of its down-stroke, has uncovered the port 44 and the expanding high-pressure air passes through said port, through the passage 43 to the small-diameter bore of the high-pressure valve-chamber, where the small-diameter valve-pistons 47 and 48, being in their down-position, connect the port 42 of said passage with the port 40 of the passage 41, and conduct the expanding air to the receiver 24. As the plunger is in its down-position, the upper annular distributing groove 16 of the high-pressure piston connects the passage 55 and port 54 from the receiver with the port 53 and passage 52 to the upper end of the low-pressure valve-chamber, so that the air from the receiver forces the low-pressure valve down. This causes the expanding air above the high-pressure piston to flow through the passage 65 to the large-diameter bore of the low-pressure valve-chamber, where the large pistons 73 and 72 now connect the port 64 of said passage to the port 62 and passage 63, admitting the expanding air to the lower end of the low-pressure cylinder where, acting against the larger piston area 15, it will force the plunger upward. The expanding live-air or high-pressure air above the high-pressure piston will also pass through the port 44, passage 43, ports 40 and 42, between the small pistons 47 and

48 of the high-pressure valve, and through the passage 41 to the receiver 24. The low-pressure air above the large piston exhausts through the passage 69, ports 68 and 70, which are connected by the small pistons 73 and 74 of the low-pressure valve, and out to the atmosphere. When the plunger arrives on its up-stroke to the point where the lower annular distributing port 17 in the high-pressure piston connects the ports 56 and 59 from the upper ends of the valve chambers with the exhaust-port 57, the air above the valves in such chambers is exhausted, and the live-air which is constantly admitted through the restricted ports 36 and 66 in the valve-chambers, will exert the differential pressure against the larger and smaller areas of the two middle pistons of the valves and, the pressure against the larger pistons prevailing, will move both of said valves upward, again repeating the operation. As now low-pressure air is stored in the receiver, such air passes through the passage 41, ports 40 and 38, which are connected by the small valve-pistons 47 and 48 in their upper position, see Fig. 1, and passage 39 into the upper end of the low-pressure cylinder, so that the expansion of this low-pressure air from the receiver also forces the plunger downward, adding strength to the blow. The air below the plunger freely exhausts through the passage 63 and ports 62 and 61 in the upper portion of the low-pressure valve-chamber, in to the atmosphere, admitting of the plunger delivering an unobstructed blow.

From the above it will appear that high-pressure air and low-pressure air simultaneously coöperate to augment the operative down-stroke of the plunger, that low-pressure air, only, is employed to return the plunger, and that the valves are actuated in one direction by low-pressure air and in the opposite direction by constant live-air pressure without exhaust, and that the only exhaust is of low-pressure air which has performed its functions, directly and expansively. After the high-pressure air has forced the piston down to deliver the blow, a part of the expanding air is directly employed to return the piston and a part is stored away in the receiver to be employed to act against the low-pressure piston of the plunger in the driving stroke of the latter and to actuate the valves. No air is exhausted excepting the low-pressure air which has been used in the low-pressure cylinder and in the valve-chamber, so that high efficiency is attained by using the air at its original pressure and thereupon again by compound use of the expanded low-pressure air exhausted from the high-pressure cylinder.

By forming the receiver from longitudi-

nal bores in the wall of the handle-socket portion of the working cylinder, such receiver does not add to the length of the tool, and the bores will reduce the weight of the 5 tool by cutting away otherwise useless material. By placing the valves and their casings at the sides of the handle-socket, the over-all length of the tool is also reduced. As the working plunger is returned by the 10 expanded live-air acting against differential piston areas, the back-stroke or up-stroke of such plunger is cushioned and shock of the tool reduced, easing the hold of the tool to the work.

15 It has been found by tests and calculation, comparing hammers in use at present and my hammer that, taking the initial air-pressure at one hundred and fifteen pounds (115 lbs.), with a two inch stroke and a cut-off at 55%, the old type hammer uses 12.4 cubic feet of air per minute, while my hammer uses 9.82 cubic feet of air per minute, being a reduction in air consumption of 2.58 cubic feet per minute or 20.8%. With the old 20 type hammer, using 12.4 cubic feet per minute, an energy of 14.17 foot pounds per stroke is developed, while my hammer develops 16.51 foot pounds of energy per stroke when using 9.82 cubic feet of free 25 air per minute. This is a gain of 16½% of foot pounds of energy on 2.58 cubic feet less air per minute.

30 During the first six or seven strokes of the hammer, when starting the same after being idle, the receiver will not be quite charged with expanded air and the air therefrom will not have quite its full pressure, but after that time, a fairly constant pressure will be maintained.

35 40 While the down-stroke of the hammering plunger is performed on the compound principle, employing live-air and the partly expanded air, or the action of high-pressure and low-pressure motive fluid combined, the compound principle is not employed for the return-stroke which is performed by differential action of the expanded or low-pressure fluid.

45 50 Other modes of applying the principle of my invention may be employed for the mode herein explained. Change may therefore be made as regards the mechanism thus disclosed, provided the principles of construction set forth, respectively, in the following 55 claims are employed.

60 It will be seen that by making the cylinder and handle with its longitudinal extension, separable, the parts can be easily machined, and by the conjunction of the handle and cylinder member, as seen in Fig. 3, I readily form the differential piston chamber, in which the differential hammering plunger or piston having the differential piston areas reciprocates. By the em-

ployment of the differential piston and cylinder with my novel fluid distribution system, it will be seen that I employ a chamber 24 to receive the exhaust and also provide means for equalizing the air pressure in the high pressure cylinder and in the low 70 pressure cylinder between the striking end of the differential piston and the shank of the working tool, thus utilizing the air in the high pressure cylinder after the receiver has been filled to return the piston:

75 I desire to call special attention to the fact that my invention in its broad aspects is especially applicable to that type of light or portable, manually held pneumatic impact tools, especially adapted for riveting, 80 chipping or analogous uses, wherein the forward end of the differential piston chamber is open for the insertion of the shank of the working tool, and wherein the differential hammering piston impacts directly upon 85 said shank of the rivet set, chisel or other working tool.

I am aware that it has heretofore been proposed to use compressed air somewhat as in a compound engine in rock drills or similar structures, which employ massive and heavy reciprocating engines frequently weighing several hundred pounds and which are required to be supported upon a suitable tripod and wherein the drill or other 90 working tool is connected to or reciprocates directly in unison with the reciprocating piston but my present invention is clearly differentiated from massive tools of this character having a comparatively slow moving piston, for the reason that my present device is particularly applicable to the small 95 manually held and controlled riveters or chipping tools, wherein the tool is supported in the hands of the operator only, and wherein the hammering piston reciprocates with great rapidity and impacts directly 100 upon the shank of the chisel, rivet set or other working tool.

105 My invention is further differentiated from the compound rock drills aforesaid or the ordinary compound engine in the matter of the motor fluid distribution. In a compound engine, the expanded fluid of the high pressure cylinders after the stroke has been completed, exhausts in its entirety to its receiver during practically all of the return stroke. In my device, the motor fluid distribution is quite different. I take a part of the expanded air of the high pressure cylinder to the receiver, from this receiver the air is taken for shifting the low pressure valve, also for the upper end of the high and low pressure cylinder to drive the piston down on its working stroke. The remainder of 115 the expanded air left in the high pressure cylinder after the receiver is filled is used 120 to return the differential plunger by a dif-

ferential pressure upon the small and large pistons. The pressure of this expanded air in the high pressure cylinder, and the pressure in the cylinder on the hammer end of the piston, equalize through a connecting passage.

It will be apparent from the diagrammatic views in Figs. 1 and 2, that the forward movement of the valves takes place at 16 about the same time that the differential plunger is impacting upon the shank of the working tool, so that the impact of the striking blow serves to more firmly seat said valves in their forward position at the 15 proper periods, so that jumping or fluttering of the valves is avoided. By the employment of the live air and partly expanded air upon the hammer or plunger during the period it is striking the blow, 20 the velocity and momentum of the reciprocating plunger is greatly augmented during the period when such increase of power is desirable, and by the employment of the differential action of the expanded and low pressure fluid to return the hammering plunger after its impact against the shank of the working tool, the expansive action of the motive fluid is utilized to the greatest extent. It will also be apparent that in my invention, by 25 the employment of the receiver and its adjuncts, the extensive vibration heretofore incident to the operation of tools of this character, particularly during riveting and chipping, is eliminated to a great extent. 30 So far as I am aware, I am the first in the art to employ a handle member having therein a high pressure inlet controlling valve, a low pressure exhaust controlling valve, and a receiver, either alone or in conjunction with the cylinder member having a 35 larger bore therein, whereby a differential piston chamber is formed. So far as I am aware, I am also the first in the art to employ in a portable, manually held, pneumatic hammer, having a cylinder provided 40 with its front end open to receive the shank of the working tool, the features of the differential hammering plunger combined with the high pressure inlet controlling valve, the low pressure exhaust controlling valve, and the receiver, whereby the motive fluid 45 may be used expansively as described in a pneumatic hammer of the character stated, and my claims to these various features are therefore to be interpreted with the corresponding scope awarded to a pioneer invention.

Having thus described my invention, what I claim as new and desire to secure by Letters Patent, is:—

1. In a pneumatic impact tool, a cylinder, a piston thereon, a valve mechanism for controlling the reciprocations of said piston, a receiver carried by said cylinder, and 65 means common to said cylinder, valve mech-

anism and receiver for operating by the pressure from said receiver, said valve mechanism, and for also effecting the returning of the piston to begin its stroke.

2. In a pneumatic impact tool, the combination of a cylinder, a piston therein, a valve mechanism, a receiver, and means for operating said piston and valve mechanism by means of the pressure of the expanded air in the receiver. 75

3. In a compound pneumatic impact tool, a small diameter cylinder, a large diameter cylinder, a small diameter and large diameter piston adapted to reciprocate in said cylinder, and means for using energy left in 80 the air after it has been used in one cylinder, for augmenting the energy of said piston.

4. In a compound pneumatic impact tool, a small diameter cylinder, a larger diameter 85 cylinder, small diameter and larger diameter plungers adapted to reciprocate in said cylinders, and means for using the energy left in the motive-fluid after it has been used in any of the cylinders for augmenting the 90 blow of said plungers.

5. In a compound pneumatic impact tool having open ends, a plurality of cylinders of varying diameter, pistons of varying diameter adapted to fit said cylinders, and 95 means for utilizing the remainder of the energy left in the expanded air after it has been exhausted from the initial pressure cylinder to increase the energy of the stroke of the piston without increase of consumption 100 of the free air.

6. In a compound pneumatic impact tool, a small-diameter and a large-diameter cylinder portion, a plunger having a small-diameter and a large-diameter piston 105 respectively reciprocable in said cylinder-portions, a receiver, and a high pressure inlet controlling valve, said small-diameter cylinder-portion having a passage near its lower end connected at intervals to said 110 receiver by said valve.

7. In a compound pneumatic impact tool, a plurality of working cylinder-portions of different diameters, a working plunger having pistons of different diameters reciprocable in said cylinder-portions, means for admitting motive-fluid to a small-diameter cylinder-portion, a receiver, means for admitting expanded motive-fluid from said small-diameter cylinder-portion to such receiver, and means for admitting expanded 115 motive-fluid from said receiver to a large-diameter piston. 120

8. In a pneumatic tool, a small diameter and a large diameter cylinder portion, a 125 plunger having a large diameter and a small diameter piston, respectively, reciprocable in said cylinder portion, a receiver, means for intermittently admitting motive-fluid into the small diameter cylinder portion, 130

- means for alternately admitting the expanded fluid exhausted from the small diameter cylinder portion to the receiver, and means for equalizing the pressure of the motive-fluid remaining in the small diameter cylinder after the receiver has been filled with motive-fluid, between the small diameter cylinder and the space in front of the large piston.
10. 9. In a pneumatic impact tool, a working-cylinder formed with a small-diameter portion and a large-diameter portion, a hammering plunger having a small-diameter and a large-diameter piston respectively slidably in said cylinder portions, means for admitting motive fluid to said small-diameter cylinder-portion, a receiver, means for admitting expanded fluid from said small-diameter cylinder-portion to said receiver, and means connected to coöperate with the motive fluid admitting means to substantially admit simultaneously expanded fluid from said receiver back of the large-diameter piston.
15. 10. In a compound pneumatic hammer, a cylinder having a differential piston chamber forming high pressure and low pressure cylinders, a plunger therein having high pressure and low pressure piston areas, a receiver, a high pressure inlet controlling valve mechanism, means controlled by the latter for simultaneously utilizing live motive fluid on the high pressure area of said plunger and expanded motive fluid from said receiver upon a large area of said plunger to drive said plunger downwardly.
20. 11. In a compound pneumatic impact tool, a small-diameter and a large-diameter cylinder-portion, a plunger having a large-diameter and a small-diameter piston respectively reciprocable in said cylinder portions, means for intermittently admitting motive-fluid into the small-diameter cylinder-portion, a receiver, means for conducting expanded motive-fluid exhausted from the small-diameter cylinder-portion to said receiver, and means for alternately admitting expanded fluid exhausted from the small-diameter cylinder-portion to the opposite end of the large-diameter cylinder-portion.
25. 12. In a compound pneumatic impact tool, a small-diameter and a large-diameter cylinder-portion, a plunger having a small-diameter and a large-diameter piston respectively reciprocable in said cylinder portions, means for intermittently admitting motive-fluid into said small-diameter cylinder-portion, a receiver, means for conducting expanded fluid from said cylinder-portion to said receiver, means connected to the motive-fluid admitting means to simultaneously admit expanded fluid from the receiver to the large-diameter cylinder-portion back of the piston in the same, and
- means for connecting the opposite ends of the cylinder-portions to admit of expanded fluid differentially acting against the pistons.
30. 13. In a pneumatic impact tool, a small-diameter and a large-diameter cylinder-portion, the latter having an opening for the shank of the working tool, a plunger having a small-diameter and a large-diameter piston respectively reciprocable in said cylinder-portions, passages connected to the opposite ends of said cylinder-portions, a receiver, a high pressure inlet controlling valve arranged to intermittently connect said passages, and a low pressure exhaust controlling valve for controlling the exhaust from said large-diameter piston.
35. 14. In a pneumatic impact tool, a small-diameter and a large-diameter cylinder-portion, a plunger having a small-diameter and a large-diameter piston respectively reciprocable in said cylinder-portions, a receiver, a passage from near the lower end of said small-diameter cylinder-portion to said receiver, means for intermittently admitting motive-fluid to the small-diameter cylinder-portion, a passage from said receiver to the upper end of the large-diameter cylinder-portion, and means coöperating with such motive fluid admitting means and controlling admission of expanded fluid from said receiver through said passage to said cylinder-portion.
40. 15. In a pneumatic impact tool, a small-diameter and a large-diameter cylinder-portion, a plunger having a small-diameter and a large-diameter piston respectively reciprocable in said cylinder-portion, a receiver, a passage from near the lower end of said small-diameter cylinder-portion to said receiver, means for intermittently admitting motive-fluid to the small-diameter cylinder-portion, a passage from said receiver to the upper end of the large-diameter cylinder-portion, means coöperating with such motive fluid admitting means and controlling admission of expanded fluid from said receiver through said passage to said cylinder-portion, a passage between the opposite ends of said cylinder-portion, and means in such passage controlling the same.
45. 16. In a pneumatic impact tool, a small-diameter and a large-diameter cylinder-portion, a plunger having a small-diameter and a large-diameter piston respectively reciprocable in said cylinder-portion, means for intermittently admitting motive-fluid into said small-diameter cylinder-portion, a receiver, a passage from near the end of said small-diameter cylinder-portion to said receiver, a passage connecting said receiver and the upper end of the large-diameter cylinder-portion, means for controlling said passage, an exhaust-passage

- from said upper end of said cylinder-portion, means for controlling said exhaust passage, a passage connecting opposite ends of the cylinder-portion, and means for controlling such passage.
17. In a pneumatic tool, a cylinder having its forward end open and adapted to receive the shank of the working tool, said cylinder having a bore of different diameters, a differential plunger having pistons of different areas, a receiver, and means for connecting opposite ends of such cylinder portions to allow expanded and exhausted fluid from a small diameter cylinder portion to act against the differential piston areas of said plunger.
18. In a pneumatic tool, a cylinder provided with a differential piston chamber having its front end open to receive the shank of the working tool, a differential plunger in said cylinder, a high pressure valve chamber on said cylinder, a high pressure inlet controlling valve therein, a low pressure valve chamber on said cylinder, a low pressure exhaust controlling valve therein, and a receiver common to said valve chambers and piston chamber.
19. In a pneumatic hammer, a cylinder having its forward end open to receive the shank of the working tool and provided with a differential piston chamber, whereby a high pressure and a low pressure cylinder is formed, a differential plunger having a low pressure piston area therein, a receiver adjacent said cylinder, a low pressure exhaust controlling valve, means controlled by said valve for enabling exhaust from said low pressure cylinder to pass to the atmosphere through said valve, and means controlled by said valve for simultaneously putting the high pressure cylinder and the chamber below said low pressure piston into communication, so that the pressure of the two chambers is equalized.
20. In a pneumatic hammer, a cylinder having its forward end open to receive the shank of the working tool and provided with a differential piston chamber, whereby a high pressure and a low pressure cylinder is formed, a differential plunger therein, a receiver adjacent said cylinder, a low pressure exhaust controlling valve, means controlled by said valve for enabling exhaust from said low pressure cylinder to pass to the atmosphere through said valve, means controlled by said valve for simultaneously putting the high pressure cylinder and the chamber below the low pressure piston into communication, so that the pressure of the two chambers is equalized, and a high pressure inlet valve mechanism for controlling the inlet and exhaust of motive fluid to said high pressure cylinder.
21. In a pneumatic impact tool, a differential valve-chamber having a large-diameter and a small-diameter bore, a differential valve having a pair of large and small diameter pistons at opposite ends thereof respectively reciprocable in said bores, said chamber having a constantly open motive-fluid inlet port at the junction of the different bores to admit such fluid to the differential areas of a small and large diameter piston, and means for admitting and exhausting fluid into and out of the end of the large-diameter bore.
22. In a pneumatic hammer, a cylinder having a differential piston chamber, the forward end of said cylinder being open for the reception of the shank of the working tool, a differential plunger in said piston chamber having pistons of different areas, a receiver, a high pressure inlet controlling valve for admitting air at initial pressure to the high pressure cylinder and at the same time admitting air from the receiver to the low pressure cylinder, and a low pressure exhaust controlling valve in communication with said receiver and said piston chamber.
23. In a pneumatic hammer, a cylinder having its forward end open for the shank of the working tool and provided with a differential piston chamber, whereby high pressure and low pressure cylinders are formed, a receiver adapted to receive the exhaust from the high pressure cylinder and retain it for use when required in the low pressure cylinder, a high pressure inlet controlling valve, and a low pressure exhaust controlling valve.
24. In a pneumatic hammer, a handle portion having an extension thereon forming a portion of the piston chamber, a cylinder member secured to said handle extension and bored to form a continuation of said piston chamber, a high pressure inlet controlling valve carried within said extension, a low pressure exhaust controlling valve carried within said extension, a receiver also located in said extension, and a piston in said piston chamber controlled by said valves.
25. In a pneumatic hammer, a cylinder member, a handle member having an extension thereon, means for securing said cylinder and handle member in assembled position, a high pressure chamber being formed in said handle extension, and a low pressure chamber being formed in said cylinder member, a differential hammering plunger, a high pressure inlet controlling valve, a low pressure exhaust controlling valve, and a receiver contained in said handle member.
26. In a pneumatic hammer, a handle portion having an extension thereon, and provided with a high pressure piston chamber, a cylinder member detachably secured to said extension, and provided with a low pressure piston chamber, a high pressure in-

let controlling and a low pressure exhaust controlling valve in said extension, a receiver also carried by said extension, and a differential piston in said piston chambers controlled by said valves.

27. In a pneumatic impact tool, a barrel formed with a large diameter cylinder portion, a handle socket connected to said barrel and formed with a small diameter cylinder portion, and a receiver consisting of longitudinal bores in the wall of said socket around said cylinder portion and connected together, a plunger having a large-diameter and a small diameter piston respectively reciprocable in said cylinder portions, and passages connecting the small diameter and the large diameter cylinder portions with said receiver, and means for controlling the flow of motive fluid to and from said plunger.

28. In a pneumatic hammer, a cylinder having a differential piston chamber, a differential plunger therein having grooves 16 and 17 therein, and an enlarged head 15, a high pressure inlet controlling valve 22, having the enlarged heads 45 and 46 and the smaller heads 47 and 48, a low pressure exhaust controlling valve 23, having the enlarged heads 72 and 73 and the smaller heads 74 and 75, means for conducting live motive fluid continuously to the space between the heads 48 and 45 and 73 and 74, a receiver, and ports and passages common to said piston chamber, receiver and valves.

29. In a pneumatic hammer, a high pressure inlet controlling valve, having the differential heads 48 and 45, a low pressure exhaust controlling valve having the differential heads 74 and 73, means for conducting live motive fluid constantly into the spaces between each of said heads, a receiver, a differential piston chamber, a differential piston therein, and ports and passages common to said receiver, valves and piston chambers.

30. In a pneumatic hammer, a handle portion having an extension thereon forming part of the piston chamber and bored to form a high pressure cylinder, a cylinder member secured to said extension and having a larger bore therein to form a low pressure cylinder, a hammering plunger having differential piston areas contained respectively in said high pressure cylinder and said low pressure cylinder, means for permitting high pressure motive fluid to act initially in said high pressure cylinder, and means for simultaneously permitting the expanded motive fluid to act upon a piston area in said low pressure cylinder to augment the force of the striking blow of the plunger.

31. In a pneumatic hammer, a cylinder member open at its forward end to receive the shank of the working tool and bored to

form a low pressure cylinder, a handle member having an extension thereon with a bore therein of less diameter forming the high pressure cylinder, whereby a differential piston chamber is formed, means for 70 securing said cylinder member and handle member together, a differential hammering plunger having piston areas of different diameters reciprocating in said differential piston chamber, a valve mechanism contained in the extension of said handle member, and ports and passages common to said valve mechanism and said differential piston chamber for admitting and exhausting motive fluid therefrom.

32. In a pneumatic hammer, a cylinder member open at its forward end to receive the shank of the working tool and bored to form a low pressure cylinder, a handle member having an extension thereon with 80 a bore therein of less diameter forming the high pressure cylinder, whereby a differential piston chamber is formed, means for coupling said cylinder member and handle member together, a differential hammering 85 plunger having piston areas of different diameters reciprocating in said low pressure cylinder and said high pressure cylinder respectively, a high pressure inlet controlling valve obtained in the extension of said handle member, a low pressure exhaust controlling valve also contained in said extension, a receiver also contained in said extension, and ports and passages common to said valves, receiver and the differential piston 90 chamber.

33. In a pneumatic hammer, a cylinder member open at its forward end to receive the shank of the working tool and bored to form a low pressure cylinder, a handle member having an extension thereon with a bore therein of less diameter forming the high pressure cylinder, whereby a differential piston chamber is formed, means for coupling said cylinder member and handle member together, a differential hammering plunger having piston areas of different diameters reciprocating in said low pressure cylinder and said high pressure cylinder respectively, said piston being provided with grooves 16 and 17, a high pressure inlet controlling valve contained in the extension of said handle member, a low pressure exhaust controlling valve also contained in said extension, a receiver also contained in said extension, and ports and passages common to said valves, receiver and the differential piston chamber.

34. In a pneumatic hammer, a cylinder having its forward end open for the shank 125 of the working tool and provided with a differential piston chamber, whereby high pressure and low pressure cylinders are formed, a receiver adapted to receive the exhaust from the high pressure cylinder 130

and retain it for use when required in a low pressure cylinder, a high pressure inlet controlling valve, a low pressure exhaust controlling valve, ports and passages common to said valves, receiver and piston chamber, and means for causing live air pressure to constantly act upon a portion of each of said valves to shift the same.

35. In a pneumatic hammer, a cylinder member open at its forward end to receive the shank of the working tool and bored to form a low pressure cylinder, a handle member having an extension thereon with a bore therein of less diameter forming the high pressure cylinder, whereby a differential piston chamber is formed, means for securing said cylinder member and handle member together, a differential hammering plunger having piston areas of different diameters reciprocating in said differential piston chamber, a valve mechanism contained in the extension of said handle member, ports and passages common to said valve mechanism and said differential piston chamber for admitting and exhausting motive fluid therefrom, and means for constantly admitting live air pressure to a portion of said valve mechanism.

36. In a pneumatic impact tool, a handle member having therein an inlet passage for the motive fluid, a high pressure inlet controlling valve, and a low pressure exhaust controlling valve in said handle member arranged at opposite sides of said inlet passage, said handle member having an exhaust passage intermediate of said valves, and a receiver contained in the upper portion of said handle member, the latter being bored to form the high pressure cylinder, in combination with a cylinder member, having a larger bore therein forming the low pressure cylinder, whereby a differential piston chamber is formed, and a differential plunger in said piston chamber, controlled by said valves.

37. As an improved article of manufacture, in a compound pneumatic impact tool, a handle member having therein an inlet passage for the motive fluid, a high pressure inlet controlling valve chamber and a low pressure exhaust controlling valve chamber, said chambers being arranged on opposite sides of said inlet passage, said handle member also having an exhaust passage therein intermediate of said valves, and a receiver in the upper portion of said handle member, the latter being bored to form the high pressure cylinder member of a compound pneumatic hammer.

38. In a compound pneumatic hammer, a handle member having an extension provided with a small bore forming a high pressure cylinder, a cylinder member attached thereto and having a larger bore therein forming a low pressure cylinder, whereby a

differential piston chamber is formed, a differential plunger located in said piston chamber, and a valve mechanism for controlling the inlet and exhaust of motive fluid to and from said piston chambers.

39. In a compound pneumatic hammer, a cylinder having therein a differential piston chamber, a differential plunger located in said piston chamber and having piston areas of different diameters, a plurality of valves for controlling the inlet and exhaust of motive fluid to and from said piston chamber, and means for causing live motive fluid to act constantly upon a portion of each of said valves for shifting the same.

40. In a compound pneumatic hammer, a cylinder having its forward end open to receive the shank of the working tool and having a differential piston chamber therein, a differential plunger located in said piston chamber and having pistons therein of different diameters, a receiver, a plurality of valves for controlling the inlet and exhaust of motive fluid to and from said piston chamber, and means for causing live motive fluid to act constantly upon a portion of each of said valves for shifting the same.

41. In a compound pneumatic hammer, a cylinder having therein a differential piston chamber, a differential plunger located in said piston chamber and having piston areas of different diameters, a receiver, and a valve mechanism for controlling the inlet and exhaust of motive fluid to and from said piston chamber, said valve mechanism comprising a plurality of valves, and means for causing live motive fluid to constantly act upon a portion of said valves for shifting the same.

42. In a compound pneumatic hammer, a cylinder having its forward end open for the reception of the shank of the working tool, said cylinder having therein a differential piston chamber, a differential plunger located in said piston chamber, a receiver, a plurality of valves for controlling the reciprocations of said piston, said valves having heads thereon of different diameters, and means for causing live motive fluid to act constantly upon the space between a pair of said heads of each valve for the purpose of shifting said valves.

43. In a compound pneumatic hammer, a cylinder member having its forward end open for the reception of the shank of a working tool, said cylinder having therein a differential piston chamber, a differential plunger located in said piston chamber, a plurality of valves for controlling the reciprocations of said plunger, each of said valves having thereon two pairs of heads of different diameters, and means for causing live motive fluid to act constantly upon the space between a small head and a large head of each of said valves for shifting the latter.

44. In a compound pneumatic hammer, a cylinder member having its forward end open for the reception of the shank of a working tool, said cylinder having therein a differential piston chamber, a differential plunger located in said piston chamber, a plurality of valves for controlling the reciprocations of said plunger, each of said valves having thereon two pairs of heads of different diameters, means for causing live motive fluid to act constantly upon the space between a small head and a large head of each of said valves, a receiver, and ports and passages common to said valves, receiver and piston chamber.
45. In a compound pneumatic hammer, a cylinder member having its forward end open for the reception of the shank of a working tool, said cylinder having therein a differential piston chamber, a differential plunger located in said piston chamber, a plurality of valves for controlling the reciprocations of said plunger, each of said valves having thereon two pairs of heads of different diameters, means for causing live motive fluid to act constantly upon the space between a small head and a large head of
- each of said valves, a receiver, and connections common to said receiver, piston chamber and one of said valves, whereby motive fluid is admitted from said receiver to act expansively upon a low pressure area of said plunger simultaneously with the admission of live motive fluid to the high pressure area of said plunger to augment the momentum of the striking blow of said plunger.
46. In a compound pneumatic impact tool, a plurality of working cylinder portions of different diameters, a working plunger having pistons of different diameters reciprocable in said cylinder portion, means for admitting motive fluid to a small diameter cylinder portion, receivers, means for admitting expanded motive fluid from said cylinders to such receivers, and means for admitting expanded motive fluid from said receivers to the cylinder portions of different diameters to augment the blow of the piston.
